UNITED STATES PATENT OFFICE.

HENRY V. BELL, OF ELMHURST, FLUSHING, NEW YORK.

COMBINATION CIRCUIT CONTROLLER.

Application filed February 12, 1921. Serial No. 444,474.

To all whom it may concern:

Be it known that I, HENRY V. BELL, a citizen of the United States, and a resident of Elmhurst, Flushing, in the county of 5 Queens and State of New York, have invented a new and Improved Combination Circuit Controller, of which the following is a description.

My invention relates to a means for vari- 10 ously completing the magneto circuit in an automobile or the like, whereby by the optional movements of selective circuit-closing and circuit-breaking elements various combinations can be brought about for the 15 completion of the circuit, the purpose being to permit the driver of the automobile to close the circuit by selectively giving positions to the movable elements and at the same time to present difficulty to one sur- 20 reptitiously endeavoring to complete the circuit after it has been broken by the driver by a displacement of the circuit-closing elements.

The nature of the invention, its distinc- 25 tive features and advantages will more clearly appear from the specific description of practical embodiments of the invention as hereinafter given.

Reference is to be had to the accompany- 30 ing drawings forming part of this specification, it being understood that the drawings are merely illustrative of practical examples of the invention.

Figure 1 is a plan view of a circuit con- 35 trolling device embodying my invention;

Figure 2 is a longitudinal vertical section on the line 2—2, Figure 1;

Figure 3 is a transverse vertical section 40 on the line 3—3, Figure 2, looking in the direction of the arrow;

Figure 4 is a section taken in the same plane as Figure 3 but looking in the reverse direction of the arrow in Figure 2;

Figure 5 is a horizontal section on the line 45 5—5, Figure 2;

Figure 6 is a perspective view of one of the movable circuit-making and breaking elements;

Figure 7 is a side elevation of one of the 50 movable elements slightly modified;

Figure 8 is a diagrammatic view of an

electric circuit formed with the device as illustrated in Figures 1 to 5;

Figure 9 is a rear elevation of that board supporting the conductor terminals disposed 55 nearest to the operator;

Figure 10 is a front elevation of that board carrying the conductor terminals and disposed remote from the operator;

Figure 11 is an elevation of the rear face 60 of the board shown in Figure 10 or that face disposed toward the operator;

Figure 12 is a plan view illustrating a modified arrangement of the conductor elements; 65

Figure 13 is a transverse vertical section on the line 13—13, Figure 12, showing the rear face of the partition or board carrying the terminals nearest the operator;

Figure 14 is a diagrammatic view of an 70 electric circuit that may be employed with the arrangement shown in Figures 12 and 13.

Referring at first more particularly to Figures 1 to 8, a frame 10 is provided having a transverse insulating board 11 at the front or that end remote from the operator, said board having terminals for a series of conductor elements as will appear, and the numeral 12 indicates a transverse partition 75 board rearward of the board 11 and carrying the terminals for the conductor elements. The numeral 13 indicates the rear end or the rear closure of the frame 10.

Between the front terminal board 11 and 85 the rear terminal board 12, I provide two series of circuit-making and circuit-breaking blocks 14, there being shown in the illustrated example an upper series of five blocks and a lower series of five blocks. The two 90 series of blocks 14 are with a view to obtain a large number of combinations in a comparatively small space. Any block of either series may be employed to complete the circuit through the terminals of the partition 95 11 or on the partitions 12 in accordance with the optional selection of the user. The blocks 14 have pairs of pins 15 projecting from the one end thereof and pairs of pro-

jecting pins 15^a at the opposite end. The 100 front pins 15 of certain blocks are of conducting material such as brass or the like,

while the front pins 15^a of the other blocks may be of insulating material, Figure 6, or, as in Figure 7 both the front and rear pairs of pins 15, 15^a, may be of conducting material.

5 In the arrangements shown in Figures 1 to 5, the insulating pins on one end of certain blocks are immaterial in said illustrated construction since not functioning as regards the making and breaking of the circuit but 10 are of more importance in the form illustrated in Figures 12 to 14 as will appear. The conductor pins are on a base plate 15^c on the block 14 so that the circuit will be completed from one pin through said base to 15 the other pin of the pair. The forward pins 15 are adapted to enter a transverse series 20 of sockets 16 in the board 11 of conducting material for completing a circuit, while the rear pins 15^a are adapted to enter conducting sockets 17 in the rear board 12. A series 25 of conductor elements 18 is provided, running from the board 11 to the board 12 and the ends thereof are adapted to be secured by binding screws or terminals 19 which are 30 adapted to engage the sockets. A similar arrangement of binding posts or terminal screws 19 is provided for securing the rear ends of the conductor elements 18 at the rear board 12.

30 The arrangement is such that the conductor elements 18 may be connected up with any of the sockets 16, 17 by shifting the binding posts or screws 19 and the conductor ends to engage particular sockets 16 or 35 17 so that the circuit will be completed through selected pairs of pins on the blocks at the boards 11 and 12. In Figures 1 to 5, two of the upper series of blocks 14 are shown in the forward positions with their 40 pins 15 in the forward sockets 16 and completing the circuit through the base plates 15^c of the respective blocks in coaction with the terminals 19 and conductor elements 18, while the central one only of the lower series 45 of blocks occupies the forward position completing the circuit through the terminals 19 on the board 11. The remaining blocks, that is to say, three in the upper series and four in the lower series, are disposed adjacent to 50 the rear board 12. The pins 15^a of all the blocks may simply have the function of frictionally engaging certain of the sockets 16, 16^a, 17, 17^a because the remaining blocks by their pins 15 complete the circuit at the 55 boards 11 and 12. Those blocks 14 functioning to complete the circuit through the sockets 17, 17^a of board 12 are reverse from the forward blocks so that their conducting pins 15 are at the rear and presented to said 60 sockets 17, 17^a to complete the circuit through the adjacent binding posts 19 on the board 12 as will be clear from the circuit diagram, Figure 8.

The binding posts 19 to which adjacent 65 conductors are connected may be coupled by

a connecting wire 20. Similarly, those binding posts 19 adjacent to one end of the board 12 may be connected by a conductor element 20^a. The supporting insulating boards 11 and 12 may have various depressions or 70 grooves 12^a, 12^b, 12^c, 12^d, to receive the conductors 18 in the different positions of the latter.

It will be understood that the detail arrangement of the conductor elements and 75 binding posts is immaterial so that a circuit is formed by conductors running back and forth between the board 11 to the board 12 alternately, the circuit to be variously completed by the blocks 14 and their pins 15 80 and bases 15^c.

Insulating partitions 21 are disposed between adjacent blocks 14, said partitions having longitudinal ribs 22 thereon which are received in corresponding grooves 23 in 85 the sides of the blocks 14 to guide said blocks in their reciprocating movements. The making of the pins 15^a and partitions 21 of insulating material in the arrangement of Figures 1 to 5 may be useful in preventing 90 jump sparks. Separate means is provided for moving each block 14 in a forward direction from a position adjacent to the partition board 12 to the front board 11, said means consisting of plunger rods 24 movable in holes 13^a in the rear closure 13 and in holes 25 in the partition 12. Springs 26 are coiled about said rods 24, the rear ends of the springs being suitably adapted to be engaged by transverse pins 24^a on said rods 95 for compressing a spring by a forward movement of a rod and causing the rod to be restored to normal position by the reaction of the spring after a forward movement of the rod. Thus, when a block has been 100 moved from a rear position adjacent to the partition 12 to a forward position to complete the circuit with the front board 11, the blocks by engagement of the pins 15 with the sockets 16, 16^a, will remain in the forward position while the plunger rods 24 will 105 be returned by the springs 26. In order to restore all the blocks that may be in a forward position a retracting head 27 is provided on a plunger rod 28 and is formed 110 with members 27^a lying in front of the several blocks 14. The plunger rod 28 has an operating head or handle 29 at the rear of the head and extends forwardly through the closure 13 and through a square hole 28^b in 115 the partition 12. The sliding of the plunger in the hole 28^b or the provision of any equivalent means is for the purpose of preventing the plunger and the head 27 from turning. A spring 30 is coiled about the plunger 28 120 and in the rearward movement of said plunger, said spring is engaged by a pin 28^a on the plunger to cause the head 27 and the plunger to be returned to the forward position. In the normal forward position of the 125 130

head 27 it is accommodated in a correspondingly shaped depression 11^c in the rear face of the board 11.

It will be seen that any of the plungers 24 may be operated to cause particular blocks 14 in the upper or lower series to move forwardly for completing the circuit by their pins 15, those ends of the conductors 18 terminating at the partitions 12 being shifted 10 accordingly for the completion of the circuit. The restoring of the forward blocks to their normal positions by means of head 27, breaks the circuit at the front board 11. On the other hand an operation of those rods 15 24 controlling the rearmost blocks 14 will 15 break the circuit at the board 12 by separating the conductor pins 15 thereof from the sockets 17, 17^a. It will be difficult, if not impossible, for an unauthorized party to ascertain 20 what blocks will need to be moved to complete the circuit and in practice the operator of an automobile will retract the plunger 27 to restore all the blocks to the rearward inoperative positions and dependent 25 on the selection of particular blocks to again complete the circuit.

In the form shown in Figures 12 and 13, Figure 14 showing the circuit diagram, the conductor elements 18^a running from the front board 11^a to the rear or partition board 12^a are in permanent positions and connect 30 in pairs to adjacent binding posts 19^a coupled by the connecting wire 20^c at both of said boards 11^a, 12^a. With the permanent 35 conductor arrangement of Figures 12, 13 and 14, the blocks 14, Figure 6, are employed with conductor pins 15 at one end and with insulating pins 15^a at the opposite end. By reversing the blocks the conductor pins 15^a 40 and their bases 15^c may be presented at the front or the rear to complete the circuit through given binding posts 19^a and leaving the circuit broken between others of the binding posts by reason of the insulating 45 pins 15^a. The character 18^c indicates the conductor ends leading into and from the frame 10 of the structure. It is to be understood that the frame as well as the operative parts of the circuit controller except the projecting ends of the rods 24, 28 are completely 50 housed in practice by any suitable means (not shown).

I would state in conclusion that while the illustrated examples constitute practical embodiments of my invention, I do not limit myself strictly to the mechanical details herein illustrated, since manifestly the same can be considerably varied without departure from the spirit of the invention as defined in the appended claims.

Having thus described my invention, I claim:—

1. A combination circuit controlling means comprising separated series of terminals, 65 conductor elements running back and forth

between said terminals and elements movable back or forth between the respective series of terminals, certain of said movable elements having members to complete the circuit at one series of the terminals, and others of said movable elements having members to complete the circuit at the terminals of the other series. 70

2. A combination circuit controlling means comprising separated series of terminals, 75 conductor elements running back and forth between said terminals and elements movable back or forth between the respective series of terminals, certain of said movable elements having members to complete the circuit at one series of the terminals, and others of said movable elements having members to complete the circuit at the terminals of the other series; together with means to restore all of said movable elements into a unitary plane, and series of individual plungers for said movable elements and optionally operable independently of one another to give movement to shift said movable elements from adjacent 80 one series of elements to the other series. 85

3. A combination circuit controller comprising separated supports, conductor elements running back and forth between said supports, means on each support to connect 95 certain of adjacent conductor elements leaving the others unconnected, and reciprocating circuit-making and breaking elements movable to or from either support and having means to variously complete the 100 circuit between unconnected conductors at the respective supports.

4. A combination circuit controller of the class described, including supports in separated planes, conductor elements running back and forth between said supports, reciprocating elements movable between said supports and coating means on said reciprocating elements and on said supports to variously complete the circuit at the respective supports through the medium of said reciprocating elements dependent on predetermined positions of the reciprocating elements relatively to the respective supports. 110

5. A combination circuit controller including supports in separate planes, conductor elements running back and forth between said supports, reciprocating elements movable to or from either support and presenting pins at both ends, conductor 115 sockets on said supports adapted to be engaged by said pins, and means on said support to variously complete the circuit from said conductor elements through said sockets and pins; together with means to actuate selectively said reciprocating elements and dispose the same adjacent to one or the other of said supports. 120

6. A combination circuit controller including supports in separate planes, conduced 130

21

tor elements running back and forth between said supports, reciprocating elements movable to or from either support and presenting pins projecting from the opposite ends thereof, the pins at one end being of conducting material and the pins at the other end being of non-conducting material, said elements being reversible to present the

conductor pins to either support and the insulator pins to the other support, and co-acting means on said supports to variously complete the circuit with said conductor elements dependent on the positions of the reciprocating elements and their pins relatively to the respective supports.

HENRY V. BELL.
